(57) **CLAIM**

I claim the ornamental design of a laser leveling apparatus, as shown and described herein.

DESCRIPTION

FIG. 1 is a perspective view of a laser leveling apparatus according to the new design.

FIG. 2 is a right side view of the laser leveling apparatus according to the new design.

FIG. 3 is a top view of the laser leveling apparatus according to the new design.

FIG. 4 is a left side view of the laser leveling apparatus according to the new design.

FIG. 5 is a front view of the laser leveling apparatus according to the new design; and,

FIG. 6 is a back view of the laser leveling apparatus according to the new design.
